(57) **CLAIM**

The ornamental design for a quick release single flashlight rail mounting system, as shown and described.

DESCRIPTION

FIG. 1 is a right elevational view of the quick release single flashlight rail mounting system, the left side elevational view being a mirror image thereof, showing our new design; FIG. 2 is a top elevation view thereof; FIG. 3 is a bottom elevation view thereof; FIG. 4 is a rear elevation view thereof; FIG. 5 is a front elevation view thereof; FIG. 6 is a top, front, left side perspective view thereof; and, FIG. 7 is a top, front, left, elevational view of FIG. 6 shown attached to a rail and flashlight thereof.

The broken line showing of a rail and flashlight, in FIG. 7, is for illustrative purposes only and forms no part of the claimed design.
